SPRINKLER HEAD

Emil Tyden, Hastings, Mich.

Application October 10, 1936, Serial No. 105,000

10 Claims. (Cl. 299—121)

This invention relates to improvements in automatic sprinklers, and is particularly concerned with certain features of a sprinkler head adapted to be mounted relatively near a vertical wall.

5 The invention includes means to ensure a proper distribution of the fire extinguishing medium so that the sprinkler head shall project the material to a considerable distance away from the wall, and at the same time discharge a sufficient, but 10 not an excessive, quantity of the material against the wall itself. The invention thus consists of certain features and elements of construction in combination as herein shown and described and as indicated by the claims.

15 In the drawing:

Figure 1 is a top plan view of a sprinkler head embodying this invention together with a diagrammatic representation of a vertical wall near which the sprinkler head is mounted.

20 Figure 2 is a side elevation of a sprinkler head indicating the contour of the deflector associated therewith and having certain parts broken away to show the method of securing the deflector in position.

25 Figure 3 is an elevation taken at right angles to that of Figure 2 and showing the discharge slot in the deflector.

Figure 4 is a detail section as indicated at line 4—4 on Figure 2.

30 In various situations it is necessary or desirable to install sprinkler heads adjacent the vertical walls of a room or enclosure instead of in the more usual arrangement, directly below the ceiling. One example of such installation is the 35 stateroom or cabin of a steamship, and in such an enclosure, when the sprinkler head is mounted relatively close to one of the vertical walls, it is necessary to provide a special form of deflector for distributing the water or other fire extinguish-

40 ing medium laterally over a sufficient portion of the room. Such a deflector must also avoid wasting too much of the water against the relatively close wall surface while providing for the discharge of a sufficient quantity in that direction.

45 In Figure 1 the sprinkler head is indicated as supported on a short horizontal section of pipe, 1, projecting from the side wall, 2, and, as shown, it is located adjacent the corner formed by the intersection of the wall, 2, and the wall, 3, of the

50 apartment. In this particular installation the sprinkler head is arranged to discharge water against both the walls, 2 and 3, within a reasonable distance of the corner, and to discharge water in the opposite direction over a large portion of 55 the room area.

The sprinkler head consists of a threaded base, 4, which is bored to provide a nozzle terminating upwardly at 5, and normally closed by means of a sealing disk, 6, and cap or valve member, 7. In the form shown the head includes an integral frame composed of two arms, 8 and 9, extending laterally from the base and curving upwardly to form a closed yoke overlying the nozzle. Directly opposite the nozzle the yoke is threaded for a set screw, 10, and the cap valve, 7, is held closed by 10 a toggle acting as a strut between the valve and the end of the screw, 10, in a well understood manner. The toggle members, 11 and 12, are formed with laterally extending arms, 13 and 14, respectively, having hook-shaped terminals which 15 are connected by a fusible link, 15, so that in the event of fire occurring in the apartment the rise of temperature in the vicinity of the sprinkler head will melt the link, 15, thus allowing the toggle, 11—12, to buckle under the pressure of water 20 in the nozzle, 5, and causing the cap valve, 7, and sealing disk, 6, to be forced open for free discharge of water from the nozzle, 5.

Such discharge will take place along the axis of the nozzle, 5, with some spreading of the stream 25 as it approaches the middle of the yoke formed by the junction of arms, 8 and 9. To control the distribution of the fire extinguishing medium a deflector plate, 16, is mounted on the yoke or frame and is formed with a substantially flat portion, 17, which is disposed opposite the nozzle mouth, 5, and overlies one arm, 9, of the yoke so as to extend at an obtuse angle to the axis of the nozzle and to the direction of flow therefrom. Thus the fire extinguishing medium, such 35 as water, which strikes this flat portion, 17, of the deflector, instead of being forced back, is shunted laterally for wide distribution over the area at one side of the sprinkler head.

The central portion of the deflector, 16, is ap- 40 pertured to fit onto a reduced neck, 18, of a central boss, 19, through which the set screw, 10, ex- tends, and this reduced neck, 18, is then peened over to secure the deflector rigidly to the frame. The portion of the deflector overlying the arm, 8, 45 is shown as curving at 20 toward the base of the sprinkler head so as to collect a considerable portion of the flow from the nozzle and direct it along the inclined surface, 17, for lateral dis- charge.

At the middle of the curved portion, 20, the deflector is formed with a slot or opening, 21, directly over the adjacent portion of the arm, 8, so that the arm is interposed between this opening and the nozzle, 5. However, the arm, 55

8, at this point is of tapered cross-section, as indicated in Figure 4, so that its surfaces meet in an edge, 22, facing the nozzle opening and diverge therefrom, thus acting to split the flow 5 from the nozzle as it approaches the curved deflector surface, 20. The portion of the deflector immediately adjacent the slot, 21, is formed into a hood at 23, which arches over the arm, 8, but out of contact therewith. Thus the stream of 10 fire extinguishing medium which is split by contact with the arm, 8, is gathered by the hood, 23, for final discharge through the opening, 21, and the two streams coming from opposite sides of the arm, 8, thus meet in or near the opening, 21, 15 and cross or merge to form a fan-like spray, serving to cover a considerable area. This spray, directed into the corner of the apartment between the walls, 2 and 3, is adequate for these surfaces adjacent the sprinkler head itself, al- 20 though it demands only a small proportion of the total flow discharged from the nozzle, 5, and the remainder of the medium is distributed in the opposite direction,—that is, laterally into the apartment,—by virtue of the deflecting ac- 25 tion of the flat portion of the plate at 17. The arm, 9, is similar in cross-section to the arm, 8, tapering divergently from an edge which faces toward the nozzle opening at 5; thus it serves to split and spread the flow of fire extinguishing 30 medium discharged by the nozzle against the deflecting surface, 17, and aids in producing a wide distribution of the medium.

Since, in many instances, as for example, in a steamship cabin or stateroom, a sprinkler head 35 of this type will be installed at a height within easy reach instead of just below the ceiling, it is desirable to lock the set screw, 10, at adjusted position to prevent tampering with the screw by unauthorized persons. For this purpose the 40 screw and the portion of the head containing it may be drilled transversely and a locking pin inserted, as indicated at 24 in Figure 2. If the nozzle should be brought into action by the occurrence of a fire, it may be understood that after 45 extinguishment of the fire the water supply through the pipe, 1, will be shut off temporarily and the entire sprinkler head will be removed and replaced instead of attempting to readjust the set screw for resetting the valve with a new fusi- 50 ble link, 15.

While there is shown and described herein cer- 55 tain specific structure embodying the invention, it will be manifest to those skilled in the art that various modifications and re-arrangements of the parts may be made without departing from the spirit and the scope of the invention, and that the same is not limited to the particular form herein shown and described, except in so far as indicated by the appended claims.

60 I claim:

1. A sprinkler having a base with a nozzle therethrough for discharge of a fire extinguishing medium, arms extending from said base to form a yoke overlying the nozzle, and a deflector 65 mounted on said yoke and having a substantially flat portion overlying one of said arms at an obtuse angle to the axis of the nozzle as measured in the plane of the yoke, said arm being formed and positioned to split and deflect said flow as it 70 approaches said flat portion, and the latter being arranged to further deflect and spread the discharge of the medium.

2. A sprinkler having a base with a nozzle therethrough for discharge of a fire extinguishing 75 medium, arms extending from said base and

forming a yoke overlying the nozzle, and a deflector mounted on said yoke and having a substantially flat portion overlying one of said arms at an obtuse angle to the direction of flow from the nozzle and a portion extending over the other arm at an acute angle to said direction of flow and trending toward the base, said last-named portion including a hood arching over said other arm out of contact therewith, and said hood having an opening for discharge of the me- 10 dium, both arms being formed and positioned to split the flow from the nozzle divergently as it approaches the deflector.

3. In the combination defined in claim 2, the opening in the hood being located directly over 15 the arm.

4. A sprinkler having a base with a nozzle therethrough for discharge of a fire extinguishing medium, arms extending from said base to form a yoke overlying the nozzle, and a deflector 20 mounted on said yoke and having a substantially flat portion overlying one of said arms at an obtuse angle to the direction of flow from the nozzle and a portion extending over the other arm at an acute angle to said direction of flow and 25 trending toward the base, said last-named portion having a slot extending over and along the arm for discharge of a portion of the medium through the deflector, and both arms being constructed and arranged to split divergently the flow 30 from the nozzle before it reaches the deflector.

5. A sprinkler having a base with a nozzle therethrough for discharge of a fire extinguishing medium, arms extending from said base to form a yoke overlying the nozzle, and a deflector 35 mounted on said yoke and having a substantially flat portion overlying one of said arms at an obtuse angle to the direction of flow from the nozzle and a portion extending over the other arm at an acute angle to said direction of flow 40 and trending toward the base, said last-named portion including a hood arching over said other arm out of contact therewith and formed with a slot directly over the arm and extending along it, said other arm being constructed and ar- 45 ranged to split the flow from the nozzle and the hood being formed and positioned for gathering said flow to produce a spreading discharge through the slot.

6. A sprinkler having a base with a nozzle 50 therethrough for discharge of a fire extinguishing medium, and a deflector fixedly mounted over said nozzle having a substantially flat portion extending obliquely with respect to the direction of flow from the nozzle, said deflector terminat- 55 ing in a portion curving toward the base, said curved portion having a single opening and the structure including an arm disposed between the nozzle and the opening in the deflector constructed and arranged for splitting the flow discharged 60 from the nozzle toward the opening.

7. A sprinkler having a base with a nozzle therethrough for discharge of a fire extinguishing medium, and a deflector fixedly mounted over 65 said nozzle having a substantially flat portion extending obliquely with respect to the direction of flow from the nozzle, said deflector terminat- 70 ing in a portion curving toward the base, said curved portion having a single opening and the structure including an arm disposed between the nozzle and the opening in the deflector constructed and arranged for splitting the flow discharged from the nozzle toward the opening, the surface of the deflector adjacent said arm converging from 75 opposite sides of the arm toward the opening and 75

being spaced from the arm to form flow passages around it.

8. A sprinkler having a base with a nozzle therethrough for discharge of a fire extinguishing medium, and a deflector fixedly mounted over said nozzle having a substantially flat portion extending obliquely with respect to the direction of flow from the nozzle, said deflector terminating in a portion curving toward the base, said 10 curved portion having a single opening and the structure including an arm disposed between the nozzle and the opening in the deflector for splitting the flow discharged from the nozzle toward the opening, the cross-section of the arm adjacent said opening being tapered divergently from the side toward the nozzle for splitting the flow therefrom.

9. A sprinkler having a base with a nozzle therethrough for discharge of a fire extinguishing medium, and a deflector fixedly mounted over 20 said nozzle having a substantially flat portion extending obliquely with respect to the direction of flow from the nozzle, said deflector terminating in a portion curving toward the base, said

curved portion having a single opening and the structure including an arm disposed between the nozzle and an opening in the deflector for splitting the flow discharged from the nozzle toward the opening, the cross-section of the arm adjacent said opening being tapered divergently from the side toward the nozzle for splitting the flow therefrom, and the surface of the deflector adjacent said arm converging from opposite sides of the arm toward the opening for gathering the 10 flow and effecting a spreading discharge through the opening. 5

10. A sprinkler having a base with a nozzle therethrough for discharge of a fire extinguishing medium, and a deflector fixedly mounted over 15 said nozzle having a substantially flat portion extending obliquely with respect to the axis of the nozzle, the structure including an arm interposed in the path of flow from the nozzle to the deflector and having a surface presented obliquely to the 20 direction of said flow for deflecting the discharge of the medium as it approaches the deflector.

EMIL TYDEN.
